UNITED STATES PATENT OFFICE.

JOSEPH MORELLI, OF BROOKLYN, NEW YORK.

FOLDABLE WINDOW-SEAT.

1,347,115.

Specification of Letters Patent. Patented July 20, 1920.

Application filed July 29, 1918. Serial No. 247,222.

To all whom it may concern:

Be it known that I, JOSEPH MORELLI, a subject of the King of Italy, and a resident of New York, borough of Brooklyn, in the county of Kings and State of New York, have invented a certain new and useful Improvement in Foldable Window-Seats, of which the following is a full, clear, and exact specification.

10 This invention relates to a class of devices adapted to be used in conjunction with the windows of buildings and other structures.

My invention has for its object primarily to provide a device or seat designed to be employed on the open window of a building or other structure whereby one or more persons may occupy the seat either in a sitting or standing posture without the occupants being liable to injury by falling from the window, and which is of a type adapted to be folded when not in use, as well as being of a form to allow the device to be detachably mounted on the window for also serving as a balcony as occasion requires. The invention consists essentially of a seat member adapted to be supported so as to extend outwardly of the window at its sill to allow one or more persons to occupy the seat member in either sitting or standing postures. 20 Hinged to the seat member is a guard member adapted to be swung from a folded position upon the seat member to a rightangular position upwardly from the seat member as well as being in spaced relation to the window, and on the seat member as well as on the window frame is provided means for detachably connecting this member to the sill of the window.

Other objects of the invention are to provide adjustable brackets whereby both the seat member and guard member may be removably fastened to the sides of the frame of the window; and to provide a window seat of a simple, efficient and durable construction which may be made in any desired shape and size.

With these and other objects in view the invention will be hereinafter more fully described with reference to the accompanying drawings forming a part of this specification in which similar characters of reference indicate corresponding parts in all the views, and will then be pointed out in the claims at the end of the description.

55 In the drawings, Figure 1 is a fragmentary view taken through the window of a building with one form of foldable seat em-

bodying my invention applied thereto, the latter being shown in side elevation and parts of which are broken away.

60 Fig. 2 is a fragmentary view showing a reduced elevation of the lower portion of the window with part of the device applied thereto.

Fig. 3 is a perspective view of one of supporting bars used in the device.

Fig. 4 is a perspective view of the device.

Fig. 5 is a detail sectional view taken on the line 5—5 of Fig. 7.

Fig. 6 is an enlarged rear elevation of the 70 device when folded.

Fig. 7 is a perspective view of the device when folded, and

Fig. 8 is an enlarged side view of one of the 75 catches used in the device.

The device has a seat member 10 which may be of any desired shape, but the form of the seat member shown is substantially rectangular to provide a front edge 11, a rear edge 12 and straight ends 13 and 14. 80 This seat member may be in the form of a board, and when made of wood it may be strengthened by fastening on its underside three spaced cross-strips, as 15, 16, 17, while on the top of the board may also be fastened 85 three strips of metal, as 18, 19, 20, of lengths so that their ends overlap the front and rear edges of the seat member besides overlapping the ends and exposed faces of the cross-strips 15, 16, 17, and all of these metal strips 90 are countersunk in the top face of the seat. I prefer to make the seat member or board 10 of a size to removably fit between the stiles 21 and 22 of the window frame, as 23, of a building or other structure so that the seat 95 member may be arranged whereby its front edge 11 will contact with the outer edge of the sill, as 24, of the window.

At the rear edge 12 of the seat member 10 is a guard member 25 which serves to prevent 100 one or more persons who may occupy the seat member from falling out of the window.

This guard member is preferably in the form of a frame of approximately a rectangular shape of a length corresponding to the length 105 of the seat member 10, while being of any desired width. This guard member or frame may be of any suitable form, though the frame illustrated is composed of a lower cross-bar 26, an upper cross-bar 27, end bars 110 28 and 29 which connect the ends of the lower and upper cross-bars, and the central parts of the lower and upper cross-bars are also connected by a cross-bar 30. Interposed in

crosswise arrangement between the bars 26, 27, 28, 29, 30 may be a number of spaced strips, as 31 and 32, and the end parts of the cross-bar 26 of the guard member are hinged, at 32 and 33, to the top of the seat member 10 to allow both of the members to be folded together as well as to permit the guard member to be swung upwardly to a rightangular position from the seat member when the device is applied to a window, as will be hereinafter more fully explained.

Serving as means to removably attach the seat member 10 to the sill 24 of the window 23, spaced parts of the top of the window sill corresponding to the spacing of the metal strips 18 and 20 may be transversely cut-out or grooved if desired. In these grooves are provided supporting bars or brackets, as 36 and 37, both of which are similarly formed. The supporting bars 36 and 37 are made of metal, and each of the bars has a straight body part, as 38, of a length to extend from the inner edge of the sill of the window to the outer edge of the sill. These body parts of the supporting bars 36 and 37 are disposed in the grooves besides being screwed or otherwise secured to the sill. On the outer end of the body part 38 of each of the supporting bars is a substantially L-shaped extension to provide a downwardly bent vertical arm 40 and a longitudinal arm 41. These L-shaped arms or extensions 40 and 41 of the supporting bars are disposed so that the vertical arms 40 are in contact with the outer edge of the window sill and so that the longitudinal arms 41 of both bars extend outwardly from the lower part of the outer edge of the sill. Projecting upwardly from the body part 38 of each of the supporting bars 36 and 37 at the juncture of the body part with the L-shaped extensions is a hook 42 which overhangs the top of the body part of the bar, and through the vertical arm of each of the L-shaped extensions is an opening 43. The openings 43 of the supporting bars 36 and 37 are in register with sockets 44 provided in the outer edge of the window sill, and adapted to be inserted in these openings and sockets are provided pins, as 45 and 46, one of which protrudes respectively from each of the metal strips 18 and 20 at the front edge 11 of the seat member 10. Movable held to the top of the metal strips 18 and 20 in proximity to the pins 45 and 46 are two hooks, as 47 and 48, which are adapted to be guided into releasable engagement with the hooks 42 of the supporting bars 36 and 37.

When the seat member 10 and the guard member 25 are folded together these members are releasably locked by providing on the central part of the front edge of the seat member an eye 49 and providing on the central part of the guard member a movable hook 50 which is moved into detachable en-

gagement with the eye 49 for fastening the seat member and the guard member together. To removably attach the seat member 10 to the window the device is arranged for inserting the pins 45 and 46 of the seat member in the registered openings 43 and sockets 44, following the unfolding of the seat member from the guard member by separating the hook 50 of the guard member from the seat member. The front edge of the seat member will then be in contact with the outer edge of the window sill, and by swinging the hooks 47 and 48 into engagement with the hooks 42 of the supporting bars 36 and 37 the seat member will be detachably held to the window to protrude outwardly of the window from its sill.

When the seat member 10 is fastened in this manner to the window sill the guard member 25 together with the seat member are also removably fastened to the stiles 21 and 22 of the window frame. To accomplish this two adjustable brackets, as 51 and 52, are provided, and both of the brackets are of similar formations. A wire 53 is disposed on the underside and lengthwise of the seat member 10 in proximity to the edge 12 of this member. The central part of this wire is fastened to the seat member, and this wire may be considerably longer than the seat member to allow loops, as 54 and 55, to be formed so as to protrude above the seat member adjacent to its edge 12 by bending the end parts of the wire upon itself and then twisting the end parts around the wire, the parts of the wire adjacent to the loops being preferably disposed in sockets 55^a and 55^b which are provided in the ends of the seat member to allow the loop to be positioned on top of the seat member. Also on the ends of the seat member 10 across the sockets may be wires, as 55^c and 55^d to prevent the loops 54 and 55 from displacement in the sockets.

To the loop 54 is movably attached a loop 56 provided on one end of a rod or wire 57 which is of a length to extend to part of the exterior of one of the stiles of the window frame considerable distance above the seat member, and the second end of this rod terminates with a loop 58. To the loop 55 of the rod 53 is movably attached a loop 59 provided on one end of a rod or wire 60 which is of a length similar to the length of the rod 57 so as to extend to part of the exterior of the second stile of the window frame above the seat member, and the second end of this rod 60 terminates with a loop 61. At the ends of the guard member 25 opposite to the hinges 32 and 33 are eye bolts, as 62 and 63, which are disposed through holes in the guard member so that their loops protrude in opposed relation to the seat member, and on the guard member may be a metal strip, as 64, to which these

eye bolts are also attached to firmly hold them to the guard member. Movable disposed in the eye of the bolt 62 is a loop 65 formed on one end of a rod 66 having a second loop 67 on its other end, and movably arranged in the eye of the bolt 63 is a loop 67^a of a rod 68 having another loop 69 on its second end. The rods 57, 60, 66, 68 are of lengths to allow their free ends to be 5 swung in close proximity to parts of the stiles of the window frame which correspond approximately to the upper edge of the guard member 25 when positioned upwardly from the seat member, and these rods are 10 also of lengths so that the loops 58 and 61 will be in register when the rods 57 and 60 are swung toward the window frame and so that the loops 67 and 69 will be in register when the rods 66 and 68 are also swung toward 15 the window frame. To detachably connect the rods 57, 60, 66, 68 to the window frame I provide two catches 70 and 71 one of which is arranged on each stile of the window frame. These catches may be of 20 any suitable types, though each of the catches is preferably composed of a screw hook 72 having a threaded stem 73 disposed right angularly from the hook, and these stems of the hooks are screwed in the exterior 25 of the stiles of the window frame so that the hooks protrude from the frame to allow the loops 58 and 61 of the rods 57 and 60 to be removably guided over the hooks. In order to also support the hooks for 30 standing a heavy load thereon in the stiles of the window frame above the hooks may be driven screws, as 74 and 75, and on each of these screws is held one end of a link 76 having its other end connected to the stem 35 73 of the hook thereunder. The free end of each of the hooks 72 is of a length to extend some distance above its stem 73, and this extending end of each hook is exteriorly threaded. On the threaded end of each hook 40 45 is screwed a nut 77, and both of the nuts are of sizes to cause the entrances into the hooks 72 to be closed after the rods 57, 60, 66, 68 are attached to the hooks.

When the seat member 10 is fastened to 50 the sill of the window, and following the upward swinging of the guard member 25 from the seat member, as above explained, the rods 57 and 66 of the bracket 51 are detachably fastened to the hook 72 of the catch 55 71 by first removing the nut 77 from the hook and guiding the loops 58 and 67 over the hook, after which the nut 77 is rescrewed on the threaded end of the hook 72. The rods 60 and 68 of the bracket 52 are detachably fastened to the hook 72 of the catch 70 in a similar fashion, and the seat member 10 together with the guard member 25 will be 60 65 removably connected to the frame of the window. In the eye bolt 62 of the bracket 51 is movably held the loop 78 of a rod 79

having a hook 80 on its second end, and in the eye bolt 63 of the bracket 52 is movably held the loop 81 of a rod 82 provided with a hook 83 on its second end. The rods 79 and 82 are of lengths so that when swung 70 accordingly their hooks 80 and 83 will respectively engage the central parts of the rods 57 and 60 of the brackets 51 and 52, and these rods will thereby be additionally reinforced to hold the seat member when 75 occupied by one or more persons. Thus I provide a simple, efficient and durable foldable seat adapted to be removably applied to the window of a building or other structure 80 for use by persons either in sitting or standing postures.

In the foregoing description, I have embodied the preferred form of my invention, but I do not wish to be understood as limiting myself thereto, as I am aware that 85 modifications may be made without departing from the principle, or sacrificing any of the advantages of this invention, therefore I reserve to myself the right to make such changes as fairly fall within the scope 90 thereof.

Having thus described my invention, I claim as new and desire to secure by Letters Patent:—

1. In combination with a window seat including a seat member having a pair of spaced pins protruding from the forward edge thereof, a pair of supporting bars for said seat member, each embodying a rearwardly projecting straight body part adapted to be secured to a window-sill and having a hook at its forward end, a vertical arm rigid with and depending from said body part and having an aperture therethrough, and a forwardly extending longitudinal arm 95 100 projecting from the bottom edge of said vertical arm and upon which said seat member rests, said pins each projecting into the aperture of one of said vertical arms, and hooks carried by the seat member adjacent 105 110 said pins and adapted to engage the hooks of the supporting bars to retain said seat member against displacement from the window-sill.

2. In combination with a window seat 115 having a pair of spaced pins projecting forwardly from the forward edge thereof, keepers adapted to be secured to a window-sill and to receive said pins, and coöoperating hooks carried by said seat and said keepers 120 for retaining the pins within the latter and the seat against displacement from the window-sill.

This specification signed and witnessed this 26th day of July, A. D. 1918.

JOSEPH MORELLI.
